UNITED STATES PATENT OFFICE.

ALBERT SCHMID AND J. CHARLES BECKFELD, OF ALLEGHENY, PENNSYLVANIA.

AIR AND GAS ENGINE.

SPECIFICATION forming part of Letters Patent No. 403,294, dated May 14, 1890.

Application filed May 17, 1888. Serial No. 274,124. (No model.)

To all whom it may concern:

Be it known that we, ALBERT SCHMID, a citizen of the Republic of Switzerland, and J. CHARLES BECKFELD, a citizen of the United States, both residing in Allegheny, in the county of Allegheny, in the State of Pennsylvania, have invented certain new and useful Improvements in Air and Gas Engines, of which the following is a specification.

10 The invention relates to the construction of engines designed to be operated by the combustion of air and gas in a closed combustion-chamber.

15 The object of the invention is to provide a convenient form of engine which may be used for various purposes, either stationary or for driving cars and other similar uses, and which will be automatic in its action when once started.

20 The invention involves certain novel constructions of apparatus for combining the air and gas under pressure, regulating the pressure in the combustion-chamber, and delivering the products of combustion to the motor.

25 The accompanying drawing is an elevation, partly in section, embodying the features of the invention.

Referring to the drawing, A represents a reservoir or tank for containing gas under any required pressure. A pipe, B, leads into the tank or reservoir for charging the same when required. The compressed air is contained in a reservoir, G. This may be charged by means of a pipe, H, leading thereto. The pipe d leads from the gas-reservoir A to a chamber, s, constituting a prolongation of the combustion-chamber S. The tube d terminates in a nozzle, s', extending within the chamber s. This nozzle extends within the cone s', in the end of which there is placed a solid deflector, s''. The entire device constitutes an injector for mingling the air and gas together. The air enters the chamber s through a pipe, d', terminating near the inner end of the cone s''. The smaller end of the cone s'' is shown as flaring outward, and this assists in securing a thorough intermixture of the gas and air. From the chamber s the mingled gas and air pass into the com-

bustion-chamber S through a perforated wall 50 or partition, t. This allows the air to pass through it, but prevents the flame in the combustion-chamber from extending back into the chamber s. As the combustion takes place in this chamber S, the expanded products of combustion pass through a tube, e, to the motor E, being delivered to the piston-cylinder e' through a governing valve, e'', in any well-known manner.

As the gas and air are burned in the chamber S, their volume increases to a very great extent, and it is always necessary to maintain the pressure in this chamber lower than that in the reservoirs A and G, otherwise the flow of air and gas from these chambers would be checked. To accomplish this, an escape-valve, O, is employed. This valve controls the opening into an escape-pipe, O'. The position of the valve is controlled by means of a diaphragm, f, or a movable piston and a spring, f''. The diaphragm is contained in a chamber, F, and one side is exposed to the pressure of the gases in the chamber S through the tube f'. A tube, f'', leads from the chamber s to the other side of the diaphragm f. If, therefore, the pressure in the chamber S becomes nearly equal to that in the chamber s, then the diaphragm will be pressed upward and open the valve O, allowing an escape from the chamber S to the open air through the pipe O', thus diminishing the pressure until the diaphragm returns to its normal position. As it is necessary that the pressure in the combustion-chamber should be slightly lower than that in the chamber s, a spring, f'', is employed, 75 which tends to move the diaphragm f in the proper direction to open the valve, the tension of the spring being adjusted to permit the proper relative pressures on the part of the gas and air in the two chambers. The 80 pressure of the spring f'' may be adjusted by means of a nut, f'''.

As is well known, the temperature occasioned by the chemical union of the air and gas by combustion is very high, and it is therefore necessary or desirable to reduce this temperature before delivering the chemically combined air and gas to the motor E. For

this purpose a tube, L, leads from the air-reservoir G to a portion, S', of the chamber S. This part of the chamber is preferably near the point at which the tube e enters, and a convenient and desirable construction is to cause the chamber S to terminate in a nozzle or pipe, l, which extends some distance into the chamber S'. The air passing from the tube L then circulates about this nozzle and 10 mingles with the product of the combustion, and reduces the temperature by uniting therewith.

For the purpose of controlling the flow of air and gas through the several tubes, d, d', and L, they are respectively provided with stop-cocks q, q', and q². These are coupled to an arm, q, which in turn is controlled by a latch-lever, Q. By means of this lever the valves may be placed in any desired position 20 and locked in a manner well understood.

The initial ignition of gas and air may be made by means of electric sparks caused to pass between two terminals or electrodes, r' and r², which are respectively connected by conductors 1 and 2 with the opposite poles of an induction-coil, V. The circuit of a battery, r, may be made and broken through a rheotoine, r², of any well-known construction, thus causing sparks to pass across from one electrode to the other. These two electrodes extend through insulated supports—such, for instance, as glass beads or tubes—into a tube or pipe, W, leading from the chamber S. This pipe extends into the escape-pipe O'. Its opening is controlled by means of a stop-cock, w. When this is open and the air and gas are allowed to flow between the points r' and r², they will be ignited if a spark is passed across the points. The cock w may then be 30 closed and the combustion will continue in the chamber S. A pressure-indicator, Z, may be applied to the chamber S or extension S', if desired.

A convenient method of charging the air and gas tanks A and G is to provide the motor E with pumping-cylinders Y' and Y², which are respectively connected with the tubes B and H. The cylinder Y' may be supplied from any suitable gas reservoir and the cylinder Y² from the open air, so that the combustion of gas and air will operate the engine, which in turn will recharge the cylinders A and G.

The form of engine here shown is stationary; but it may readily be adapted to street-car purposes and various other uses without departing from the spirit of the invention.

We claim as our invention—

1. The combination of a gas-reservoir, an air-reservoir, a mixing-chamber, a combustion-chamber into which the mingled gas and air is delivered and in which it is burned, and an automatic pressure-regulating device determining an unchangeable excess of pressure in the mixing-chamber above that in the combustion-chamber.

2. In an air and gas engine, a mixing-chamber, a combustion-chamber, and an outlet from the combustion-chamber to the atmosphere, in combination with a regulating device for determining the relative opening of the outlet from the combustion-chamber to the atmosphere. 70

3. The combination of an air-reservoir, a gas-reservoir, a mixing-chamber, a combustion-chamber, an escape-tube from the combustion-chamber, a movable body, connections from the mixing-chamber to one side of the movable body and connections from the combustion-chamber to the other side of the movable body, and a valve for the escape-tube whose position is controlled by the relative pressures upon the two sides of the movable body. 75

4. In an air and gas engine, a combustion-chamber and a pressure-regulator therefor, consisting of a movable body, a chamber including the same, a spring exerting a tension in one direction upon the movable body, an outlet from the combustion-chamber controlled by the position of the movable body, and openings upon opposite sides of the chamber from the combustion and the air and gas chambers, respectively. 85

5. The combination of an air-reservoir, a gas-reservoir, a mixing-chamber, tubes leading from the reservoirs to said mixing-chamber, a combustion-chamber, an escape-tube from the combustion-chamber, a diaphragm, connections from the mixing-chamber to one side of the diaphragm, connections from the combustion-chamber to the other side of the diaphragm, a valve for the escape-tube whose position is controlled by the relative pressures upon the two sides of the diaphragm, 95 and a spring exerting its pressure upon one side of the diaphragm. 100

6. In an air and gas engine, a mixing-chamber receiving air and gas, a combustion-chamber, and an intervening perforated wall or burner, in combination with a regulating device for predetermined a fixed and constant excess of pressure on the mixing-chamber side. 110

7. In an air and gas engine, the combination, with the combustion-chamber and the tubes supplying air and gas to the same, of an independent air-supply tube terminating in the combustion-chamber, and a regulating device operating to permit a continuous flow of air to the combustion-chamber through the independent air-supply tube. 115

8. In an air and gas engine, the combination of the air and gas reservoirs, the mixing-chamber, the tubes leading thereto from the air and gas reservoirs, the cooling-chamber, and the tube leading from the air-reservoir to the cooling-chamber, with a regulating device operating to permit a continuous flow of air to the cooling-chamber and thence through the regulator-valve to the atmosphere. 125

9. In an air and gas engine, the combina-

tion of air and gas reservoirs, the mixing-chamber, the tubes leading thereto from the air and gas reservoirs, the cooling-chamber, the tube leading from the air-reservoir to the cooling-chamber, valves for controlling the openings of the respective tubes, and a lever for controlling the position of all of said valves simultaneously.

In testimony whereof we have hereunto subscribed our names this 14th day of May, A. D. 1888.

ALBERT SCHMID.
